UNITED STATES PATENT OFFICE.

DONALD McEACHERN, OF ARGYLE, ONTARIO, CANADA.

TOOTH-BRUSH.

No. 914,501.

Specification of Letters Patent.

Patented March 9, 1909.

Application filed April 6, 1908. Serial No. 425,485.

To all whom it may concern:

Be it known that I, DONALD McEACHERN, of Argyle, in the Province of Ontario, Canada, have invented certain new and useful 5 Improvements in Tooth-Brushes, of which the following is a specification.

My object is to devise a tooth brush in which is provided a suitable retainer for a liquid dentifrice and water, and means for 10 holding the bristles in shape and which is nevertheless as simple and cheap to construct as a brush of ordinary construction.

A brush constructed in accordance with my invention comprises a back in which 15 tufts of bristles are set in the ordinary way, and an inwardly inclined wall surrounding the tufts or bristles but only in contact with the bristles at its upper inner edges, thus leaving a reservoir surrounding the bases of 20 the tufts of bristles.

Figure 1 is a side elevation of a brush constructed in accordance with my invention, the head of the brush being in section. Fig. 2 is a cross section through the head of 25 the brush on an enlarged scale. Fig. 3 is a plan view of the brush with the bristles removed.

In the drawings like letters of reference indicate corresponding parts in the different 30 figures.

A is the brush handle, of any desired shape, and provided with the hole a by means of which it may be hung to a suitable peg.

35 The head B of the brush has an oblong recess cut therein to form walls C integral with the back D. The sides of the recess are undercut so that the walls C incline inwardly from opposite sides. The ends of 40 the recess are also undercut, particularly the rear end, the undercutting of the forward end of the recess not being of so much importance.

In the back at the bottom of the recess are 45 formed a plurality of rows of holes b in which are inserted the tufts of bristles E. The holes, it will be seen, are set inwardly from the bases of the side walls so that an unperforated portion of the back is left be- 50 tween the outer rows of holes and the side walls. The walls are of such a height and so inwardly inclined that they contact with the sides of the outer rows of tufts of bristles at a point intermediate their fixed and 55 free ends.

It will be seen, particularly on reference to the sectional views, that a reservoir is thus formed at each side of the bristles of the brush, each of which reservoirs is substantially triangular in cross section, and 60 which is substantially closed at its outer side by the contact of the side wall with the bristles. This construction of the brush enables a liquid dentifrice to be used to the greatest advantage as any such liquid applied to the brush accumulates in the reservoirs, and when the brush is tilted to the position in which it is used the liquid flows from the reservoir to the bristles, flowing 65 along them partly by gravity and partly by capillary attraction till the points of the bristles are reached.

The importance of the inner upper edges of the side walls touching the bristles will readily be understood, as otherwise when 75 the brush was tilted the liquid instead of being conducted to the bristles would simply flow out of the lower reservoir over the side wall. The contact of the inner upper edges of the side walls with the bristles also 80 serves the function of holding the bristles in shape without interfering in any way with their free elastic action.

The comparatively deep undercutting of 85 the rear end of the recess is of importance as the brush is usually held with the handle lower than the head of the brush and the liquid used therefore naturally tends to flow toward the handle. The comparatively 90 large reservoir formed at this point serves to retain the dentifrice, and from it the dentifrice will flow when the brush is inserted in the mouth and turned to the horizontal position.

95 My brush not only possesses important advantages in use, but will cost no more to construct than the ordinary brush, and will be just as durable.

The head of the brush is all in one piece, 100 and the bristles are connected to the back in the ordinary manner, the extra material in the side walls and the extra labor of shaping being practically negligible quantities.

105 What I claim as my invention is:—

1. A brush head having an oblong recess with undercut side walls formed therein and a plurality of rows of holes at the bottom of the recess, an unperforated portion being left between the outer rows of holes 110

and the side walls of the recess, in combination with tufts of bristles set in said holes and projecting from the recess.

2. A brush head having an oblong recess with undercut side and rear end walls formed therein and a plurality of rows of holes at the bottom of the recess, an unperforated portion being left between the outer rows of holes and the side walls of the re-

cess, in combination with tufts of bristles 10 set in said holes and projecting from the recess.

Argyle, Ont., 2nd April, 1908.

DONALD McEACHERN.

Signed in the presence of—

JOHN G. RIDOUT,
BELLE LOGEE.
